UNITED STATES PATENT OFFICE

137,270

DESIGN FOR A COMBINED WATCH AND MIRROR

Albert F. Ouellet, New York, N. Y.

Application July 8, 1943, Serial No. 110,631

Term of patent 14 years

To all whom it may concern:

Be it known that I, Albert F. Ouellet, a subject of the King of Great Britain and a resident of the city of New York (Borough of Manhattan) county and State of New York, have invented a new, original, and ornamental Design for a Combined Watch and Mirror, of which the following is a specification, reference being had to the accompanying drawing forming part thereof, in which

Fig. 1 is a rear view of a watch embodying my design.

Fig. 2 is a side view partly in section thereof.

Fig. 3 is a front view thereof.

The dominant feature of my design resides in the provision of a concave mirror on the back of the watch.

I claim:

The ornamental design for a combined watch and mirror, as shown and described.

ALBERT F. OUELLET.
